UNITED STATES PATENT OFFICE.

EARL D. ESREY, OF DEER PARK, NEW YORK.

TABLE.

1,217,730.

Specification of Letters Patent.

Patented Feb. 27, 1917.

Application filed February 16, 1915. Serial No. 8,505.

To all whom it may concern:

Be it known that I, EARL D. ESREY, a citizen of the United States, residing at Deer Park, in the county of Orange and State of New York, have invented certain new and useful Improvements in Tables; and I do hereby declare the following to be a full, clear, and exact description of the invention, such as will enable others skilled 5 in the art to which it appertains to make and use the same.

This invention relates to tables, and the primary object of the invention is to provide a table having a section of its top rotatable independent of the remainder thereof for facilitating the positioning of certain parts of the rotatable section of the table top convenient to persons positioned at various places about the table.

Another object of this invention is to provide a table as specified which has a rigid top provided with an opening extending through the central portion thereof in which is rotatably mounted a segment of the top, 20 having its upper surface lying flush with the stationary section of the table top, and to provide handles extending upwardly diagonally from the rotatable section of the top, and further to provide a groove formed in 25 the rigid top surrounding the outer marginal edge of the opening for allowing for the movement of the hand grip carried by the rotary section.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:—

Figure 1 is a top plan view of the improved table,

Fig. 2 is a cross sectional view on the line 2—2 of Fig. 1, and

Fig. 3 is a side elevation of the improved table, showing one of the uses of the same.

Referring more particularly to the drawings, 1 designates a rigid section of the table top, which is supported by legs 2 of any ordinary construction, and which is provided 55 with an opening 3 extending through the central portion of the top, which opening is

preferably circular shaped in plan. The rigid top 1 of the table has a flange 4 formed upon the wall of the opening 3 at the lower edge or surface of the table, which flange 60 projects inwardly toward the central axis of the opening 3 and forms a rest for the rotatable section 5 of the table top. The rotatable section 5 of the table top is seated within the opening 3 and has its upper surface 65 lying flush with the upper surface of the rigid section 1 of the table top. The rotatable section 5 has hand grips 6 secured to the periphery of the same, which hand grips extend diagonally upward from the section 70 5, above the upper surface of the same so as to permit of rotary movement of the rotary section 5 by the hand grips 6. The rigid top 1 of the table has the upper corner of its inner edge which surrounds the opening 3 cut 75 away, as is indicated at 7, so as to permit of a free unimpeded movement of the hand grips 6. A section of the rigid top 1 which surrounds the cut away portion is inclined and extends substantially parallel to the 80 hand grips 6.

The rotary section 5 of the table top has a spindle 8 secured to the under surface thereof, and depending therefrom. The spindle 8 is rotatably carried by a sleeve 9, which 85 sleeve is supported by horizontally positioned braces 10 which extend from one of the supporting legs 2 of the table to the other. If it is so desired, the spindle 8 may have its upper end enlarged, as is shown at 90 11, providing a substantially frusto-conically shaped head which rests in the recess 12 formed in the upper end of the sleeve 9, which recess communicates with the bore of the sleeve, as is clearly shown in Fig. 2 of 95 the drawing.

In Fig. 3 of the drawings, one of the many uses of the table is illustrated. The rotary section 5 of the table top has a cabinet 20 mounted thereon, which cabinet is provided 100 with a plurality of vertical and horizontal partitions 21 and 22 respectively, dividing the interior of the same into a plurality of pigeon-holes for use in storing various types of documents or the like.

The improved table may be put to a number of different uses, among which are; used as a dining table, by means of which the various dishes may be moved about within easy reach of the different persons seated at 110 the table; a table for use in an office or the like, at which time the cabinet 20 might be

2
employed for the storage of documents, and the rigid top used for the usual purposes to which an office table is applied; the table might also be used for displaying of various articles, or any other uses not mentioned.

From the foregoing description taken in connection with the accompanying drawings the advantages of construction and of the method of operation of the improved table 10 will be readily apparent to those skilled in the art to which this invention appertains and, while in the foregoing description, the principle of the operation of this invention has been described together with various 15 features of construction, it is to be understood that certain minor features of construction, combination and arrangement of parts may be altered to suit practical conditions provided such alterations are comprehended within the scope of what is claimed.

Having thus fully described the invention, what is claimed is:—

In a table structure, a rigid top, a plurality of legs supporting said top, said top provided 25 with a centrally disposed opening, and having an inwardly extending annular flange formed

upon the lower edge of the wall of the opening constituting a supporting flange, a rotatable top rotatably mounted within said opening and resting upon said flange, the upper surface of said rotatable top lying flush with the upper surface of said rigid top, a vertical sleeve supported by said legs and having its upper end concentrically related with said opening in the rigid top, and provided with an inwardly extending bore having its upper end terminating in a recess having inclined walls, a substantially vertical spindle rotatably mounted in said bore of the sleeve, the upper end of said spindle being frusto-conical and resting within said recess constituting a bearing, said enlarged end of the spindle being secured to the underside of the rotatable top centrally thereof as and for the purpose specified.

In testimony whereof I affix my signature in presence of two witnesses.

EARL D. ESREY.
